UNITED STATES PATENT OFFICE.

JOHN HEINO, OF NEW YORK, N. Y.

PHONOGRAPH-NEEDLE.

1,343,507.

Specification of Letters Patent. Patented June 15, 1920.

Application filed April 10, 1919. Serial No. 269,087.

To all whom it may concern:

Be it known that I, JOHN HEINO, a citizen of Finland, and a resident of the city of New York, borough of Bronx, in the county of Bronx and State of New York, have invented a new and Improved Phonograph-Needle, of which the following is a full, clear, and exact description.

This invention pertains to a phonograph needle which it shall not be necessary to renew after each record has been played, as is now customary.

It is well known that needles have been put on the market, known as "tungsten" needles, which consist merely of a body of suitable metal to which is welded, or otherwise secured, a point of extremely hard metal, with which approximately from ten to twenty-five records can be played without renewing the needle. However, due to the great hardness of the actual playing point of this needle, it wears the records excessively and results in such records becoming very scratchy after being used a comparatively short time only.

My invention contemplates the provision of a phonograph needle which may be utilized any number of times, but in which the actual playing point is not of sufficient hardness to damage the record.

A further object of this invention is to provide a needle of this style in which the playing point may be renewed without the exercise of any mechanical skill whatsoever.

A final object of this invention is the provision of a needle of the above-mentioned class which shall incorporate means for holding the playing point so firmly that it is impossible that any slipping of the same might occur, but which shall, nevertheless, be capable of being instantly loosened, so that the playing point may be fed forward and the needle be good for any number of subsequent playings.

Reference is had to the accompanying drawings which illustrate one practical embodiment of my idea and in which—

Figure 1 is a sectional side elevation of my improved needle;

Fig. 2 is a plane side elevation; and

Fig. 3 is a sectional view taken along the lines A—A of Fig. 1.

In these figures, 1 designates the needle, or point, holder, which comprises a body

provided with a longitudinal bore, as indicated at 2, and a slot extending throughout its entire length from the outer face of the body 1 through to the bore 2, as indicated at 3. A filler 4 is mounted within the bore 2, such filler including a material which may be of any suitable hardness, for engaging the grooves on a record and transmitting the vibrations on the face of such record to the diaphragm of the receiver.

As is obvious, the filler 4 is slidable within the bore 2, and to retain this filler in its suitable position, I provide clamping means for engaging the filler, and by constricting the bore render such filler movable. This clamping means, briefly stated, comprises a nut 5 mounted upon screw threads 6 formed upon a tapering end portion 7 of the body 1. The slot 3 is provided with branch slots 8 near its upper end, and terminating in such branch slots and extending therefrom downwardly to a point adjacent the tapered end portion of the body 1, is a T-shaped rib 9, the lower part of whose body is wedge shape and has its outer face provided with screw threads, as indicated at 10.

In operation it will now be seen that granting that the point of the filler 4 has become worn, and it is desired to feed a certain amount of the same downwardly through the bore 2, so that subsequent records to be played can be reproduced, all that it will be necessary for the operator to do is to turn the nut 5 in a clockwise direction, whereupon the rib 9 will become slightly unseated and the bore 2 adjacent the nut 5 will enlarge sufficiently for the filler 4 to be slid downwardly to a sufficient extent, it being noted, however, that longitudinal shifting of the rib 9 is prevented by means of the cross-arms of the T-shaped rib 9 which fit into the slots 8. Upon this operation being completed, all that it is necessary for the operator to do is to reverse this procedure, by simply turning the nut 5 in an anti-clockwise direction, whereupon the bore 2 adjacent the nut will be constricted and the rod 9, by virtue of its wedge shape and screw threads 10, will be forced inwardly and firmly engage the filler 4 and press the same against the opposite face of the bore 2 and prevent any movement of such filler with respect to the body 1.

Having thus described my invention, I

claim as new and desire to secure by Letters Patent:

A phonograph needle, including a body provided with a longitudinal bore extending through its entire length, a slot extending from the bore to the exterior surface of the body, such slot being provided

with a pair of branch arms, a T-shaped rib mounted within such slot and its branch arms, a filler within such bore, and means for constricting the bore and pressing the rib firmly thereinto to retain the filler in applied position.

JOHN HEINO.
